(57) CLAIM

The ornamental design for a table, as shown and described.

DESCRIPTION

FIG. 1 is a perspective view of the table;

FIG. 2 is a front elevational view of the table;

FIG. 3 is a rear elevational view of the table;

FIG. 4 is a right side elevational view of the table, the opposite side of which is a mirror image;

FIG. 5 is a top plan view of the table; and,

FIG. 6 is a bottom plan view of the table.

The broken lines in the figures represent portions of the article which form no part of the claim.
